SHIELD FOR NEON TUBES

Le Roy S. Steinbacher and Raymond W. Taylor,
Battle Creek, Mich.

Application March 12, 1934; Serial No. 715,232

9 Claims. (Cl. 40—130)

This invention relates to a shield designed primarily for use in connection with electrical signs or other displays utilizing neon tubes whereby interference with radio reception can be prevented.

As is well known to those skilled in the art luminous displays of this type are formed of a continuous tube bent to any desired shape and provided with electrodes, the tubes being filled with a gas such as neon, argon, helium or the like meeting the requirements. To each end of the tubing at the point of the electrode is connected a high voltage secondary lead from a transformer. The signs to which we particularly refer are of the type not mounted to a metal cabinet with power transformer and high voltage secondary leads enclosed in said cabinet. The operation of the tubes containing luminous gas results in the emanation of radio-active waves or radiations which interfere with the proper reception of radio signals.

It is an object of the present invention to provide a novel form of shield for use in connection with an unenclosed sign or the like whereby the radio-active emanations will be absorbed and the operation of the display device can be carried on without interfering with radio reception.

A further object is to provide a shield made up of adjustably mounted panels which can be shifted angularly relative to each other so as to be placed in the most advantageous shielding positions necessary for the particular display device with which they are used.

Another object is to provide a shield of this character which is simple, compact, and efficient and can be set up readily without requiring the services of a skilled mechanic.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred forms of the invention have been shown.

In said drawings

Figure 1 is a front elevation of a neon sign behind which is supported a shield such as constitutes the present invention, the electrical connections being illustrated in diagram.

Figure 2 is a rear elevation of the shield.

Figure 3 is a plan view of the sign and shield taken on line 3—3, Figure 1.

Figure 4 is a section on line 4—4, Figure 1, the adjacent portion of the sign being shown in plan.

Figure 5 is a plan view of a modified form of shield.

Figure 6 is a front elevation of a portion of another form of shield.

Figure 7 is a front elevation of a portion of another modification.

As has already been stated the improvements constituting the present invention can be used in connection with any display device utilizing electrically charged luminous gas from which radioactive waves emanate. The shield can be made in various designs and of different materials of proper conductivity, it being understood that the metal used, the type of shield employed, and the area of the shield as well as the location of the parts in order to obtain the best results will all depend upon the nature of the display device with which it is associated. Various forms of the shield can be used and it has been deemed advisable in the present instance to show and describe four of them.

In the structure illustrated in Figures 1 to 4 inclusive there is provided a metal frame 1 the top and bottom members 2 of which provide bearings for the ends of parallel rods 3. These rods can be rotatably mounted or they can be stationary. On each of the rods is mounted a metal panel 4. If the rods rotate the panels can be secured to them. If the rods are not rotatable the panels can rotate upon them. All of the panels are so spaced and proportioned that when they are aligned they will practically fill the space defined by the frame 1.

Each of the panels is provided with an ear 5 extending from one edge thereof and, in the structure referred to, all of these ears are pivotally connected at 6 to a connecting bar 7 extending longitudinally of the frame. Thus by moving the bar in one direction or the other the panels 4 constituting the shield members will be moved in unison relative to each other and about their respective fulcrums so as to be disposed at any desired angle relative to the frame 1.

In practice a shield which is substantially co-extensive with the sign with which it is to be used, is suspended in any suitable manner back of the sign, wires or cords W being used for this purpose. Under some conditions the frame can be grounded as shown at G.

It is essential that the shield be placed at a sufficient distance from the sign to permit angular

adjustment of the shield panels. After the sign has been energized the panels are adjusted angularly until they are brought to such position as to absorb the objectionable emanations from the 5 glowing gas and after this adjustment has been effected it has been found, in actual use, that there will be no objectionable interference to the reception of signals by radio receivers. Obviously the angles of the panels must be adjusted 10 to meet the requirements of the particular electrical device with which the shield is used and for that reason the employment of adjustable shield panels is essential.

Under some conditions it has been found 15 advantageous to arrange the panels so that one or more of them can be adjusted independently of the others. This is especially desirable where the emanations from one part of a sign cover a greater area or are stronger than those from another 20 part of a sign. As shown in Figure 5 the panels 8 can be located in groups, the panels of each group being connected by a bar 9 and each bar being shiftable independently of the other.

In practice it has been ascertained that it is 25 not always desirable to employ shield panels which are solid. For example, and as shown in Figure 6, each panel 10 can be formed of a metal screen. Under other conditions the shield can be made of a frame 11 having spaced openings 12 and in this frame can be mounted a slide 13 having 30 openings forming shield panels 14 therebetween movable into and out of register with the openings 12. Thus by shifting slide 13 (see Figure 7) the shielding area exposed to the sign can be increased or reduced as found necessary.

As before stated various other modifications of 35 adjustable shields might be used with a luminous sign of the type mentioned without departing from the spirit of the invention as claimed. Furthermore it need not be necessary under all 40 conditions to provide an adjustable shield. For example a single piece of conductive material cut to proper size and placed in proper position relative to the sign tubing but not fast to the tubing 45 will accomplish the desired result under some conditions.

What is claimed is:

1. A shield for use in connection with electrical display devices utilizing luminous gas, which 50 includes a frame, and a plurality of shield panels adjustably mounted within the frame for varying the shielding area exposed to said device.

2. A shield for preventing radio interference by neon signs or the like of the type not connected to or associated with a metal cabinet, said 55 shield comprising a frame adapted to be sus-

pended in close proximity to the sign and shield panels mounted within the frame and adjustable to vary the area exposed to the sign or the like.

3. A shield for preventing radio interference by neon signs or the like of the type not connected to or associated with a metal cabinet, said 80 shield comprising a frame adapted to be suspended back of and adjacent to the sign or the like and a plurality of shield panels mounted for rotation relative to each other within the frame 85 thereby to vary the area exposed to the sign or the like.

4. A shield for preventing radio interference by neon signs or the like of the type not connected to or associated with a metal cabinet, said 90 shield comprising a frame, and a plurality of shield panels mounted for rotation therein about parallel axes.

5. A shield for preventing radio interference by neon signs or the like of the type not connected to or associated with a metal cabinet, said shield comprising a frame, and a plurality of screen shield panels mounted for rotation therein about 95 parallel axes.

6. A shield for preventing radio interference by neon signs or the like of the type not connected to or associated with a metal cabinet, said shield including a frame having spaced openings, and a plurality of connected panels shiftable relative to the openings for varying the area exposed to the 105 sign or the like.

7. A shield for preventing radio interference by neon signs or the like of the type not connected to or associated with a metal cabinet, said shield including a frame having spaced openings, and a plurality of connected panels slidable relative to the openings for varying the area exposed to the sign or the like.

8. A shield for preventing radio interference by neon signs or the like of the type not connected to or associated with a metal cabinet, said shield comprising members of conductive material suspended adjacent to but not connected with the sign, said members being shiftable to vary the 115 degree in which they function as a shield.

9. The combination with a neon sign or the like of the type not connected or associated with a metal cabinet, of a shield for absorbing and eliminating radiations from the sign in any direction, said shield comprising a sheet of conductive material of an area substantially equal to that occupied by the sign, said shield being suspended adjacent to but not connected with the sign.
